(57) **CLAIM**

The ornamental design for cedar shears, as shown and described.

DESCRIPTION

FIG. 1 is a bottom perspective view of the cedar shears, showing my new design;

FIG. 2 is a top perspective view of the cedar shears;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is another perspective view thereof.

The broken lines represent portions of the cedar shears and form no part of the claimed design.

The shears are shown with a symbolic break in the length of the handles. The appearance of any portion of the article between the break lines forms no part of the claimed design.
